CLAIM

The ornamental design for a combined golf accessory tool with holder and golf ball marker, as shown and described.

DESCRIPTION

FIG. 1 is a perspective view of a combined golf accessory tool with holder and golf ball marker showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view of the combined golf accessory tool with holder and golf ball marker, with the ball marker removed;

FIG. 8 is a front elevational view of FIG. 7;

FIG. 9 is a right side elevational view of FIG. 7;

FIG. 10 is a left side elevational view of FIG. 7;

FIG. 11 is a top plan view of FIG. 7;

FIG. 12 is a bottom plan view of FIG. 7;

FIG. 13 is a perspective view of the golf ball marker;

FIG. 14 is a front elevational view of FIG. 13;

FIG. 15 is a side elevational view of FIG. 13; and,

FIG. 16 is a bottom view of FIG. 13.
